UNITED STATES PATENT OFFICE.

SAMUEL M. RIKER, OF CHESTER, NEW JERSEY.

EMBROIDERY NEEDLE.

Application filed June 22, 1921. Serial No. 479,701.

To all whom it may concern:

Be it known that I, SAMUEL M. RIKER, a citizen of the United States, residing at Chester, in the county of Morris and State 5 of New Jersey, have invented certain new and useful Improvements in Embroidery Needles; and I do hereby declare the following to be a full, clear, and exact description of the invention, such as will enable 10 others skilled in the art to which it appertains to make and use the same, reference being had to the accompanying drawings, and to characters of reference marked thereon, which form a part of this specification.

15 This invention has reference, generally, to improvements in needles; and, the present invention relates, more particularly, to a novel construction of embroidery needle, provided with a channelled handle or shank 20 in which the embroidery silk, cotton, floss, in the form of a thread, is threaded, and to which the embroidery needle is detachably and adjustably connected, the said channelled handle or shank being further provided with a suitably disposed thread-re- 25 ceiving guide or guides.

The invention relates, furthermore, to a novel embroidery needle, the handle or shank of which is provided with a thread-engaging means, preferably in the form of a pivoted clamp adapted to be actuated by the operator to tighten the embroidery loop of the thread and to prevent pulling of the thread from the material, as the same is being 30 embroidered.

35 The present invention, therefore, has for its principal object to provide a novel and simply constructed embroidery needle, which prevents pulling of the thread upon the re- 40 turn-stroke of the needle from the material, the thread, furthermore, being held taut, so that the embroidered surface is devoid of any loose thread-positions, and that a perfectly smooth embroidered surface will be 45 produced.

Other objects of the present invention not at this time more particularly enumerated will be clearly understood from the following detailed description of the same. With 50 the various objects of the present invention in view, the said invention consists, primarily, in the novel embroidery needle here-

inafter set forth; and, the said invention consists, furthermore, in the novel arrangements and combinations of the various devices and parts, as well as in the construction of the said parts, all of which will be more fully described in the following specification, and then finally embodied in the clauses of the claims which are appended to and which form an essential part of the said specification.

The invention is clearly illustrated in the accompanying drawings, in which:—

Figure 1 is a face-view of an embroidery 65 needle, showing one embodiment of the principles of the present invention, said view illustrating also the use of the needle in connection with the fabric which is being embroidered.

70 Figure 2 is a cross-sectional representation of the needle, said section being taken on line 2—2 in said Figure 1, and the said view being made on an enlarged scale.

75 Figure 3 is a view of a fragmentary portion of the handle or shank of the needle, said view being also made on an enlarged scale, said view showing in connection therewith, one arrangement of thread-retaining loop or guide; and Figure 4 is a cross-sectional representation of the needle, said section being taken on line 4—4 in said Figure 1, said view being also made on an enlarged scale.

80 Figure 5 is a longitudinal vertical section 85 representation of a fragmentary portion of the handle or shank of the needle, and of a thread-engaging means or clamp pivotally connected with the said handle or shank, said view being also made on an enlarged scale; and Figure 6 is a transverse sectional representation of the same, said section being taken on line 6—6 in said Figure 5.

90 Similar characters of reference are em- 95 ployed in all of the said above described views, to indicate corresponding parts.

Referring now to the said figures of the drawings, the reference character 1 indicates a complete embroidery needle made according to and embodying the principles of the present invention.

100 As shown in the several figures of the drawings, the handle of the embroidery-

needle is usually made from a piece of sheet-metal 2 which is suitably bent or curved, so as to provide a longitudinally extending groove or channel, as 3, bounded by the 5 curved and longitudinally extending marginal portions 4 and 5, with which are connected and extend angularly and rearwardly, a pair of members or sides, as 6 and 7, meeting at their marginal edges 8 and 9, substantially in a manner as shown in Figures 10 2 and 6 of the drawings. At its lower end-portion, the said handle has a tubular extension 10, in alignment with the said longitudinally extending groove or channel 3, 15 said extension, as will be seen from an inspection of Figure 4 of the drawings, being of circular configuration in transverse section, and having a longitudinally extending slit 11, bounded by the marginal edges 20 13 and 14, one of which, as 14, being provided with a plurality of laterally extending and short slits or open portions 15. At its lower extreme end, the said tubular extension 10 is made with oppositely projecting 25 wings 16 and 17 with which are connected and extend laterally and forwardly beneath the end of said extension 10, a pair of arc-shaped members 18 and 19 terminating in front near each other in an opening 30 20, as will be clearly evident from an inspection of Figure 4 of the drawings. The said channelled or grooved handle of the embroidery needle may also be provided at any suitable point or points with an outwardly and inwardly curved member 21, 35 preferably forming an integral portion of the said handle-body, said member thus providing a suitable thread-receiving loop or guide, as will be clearly evident from an 40 inspection of Figures 1, 2, and 3 of the drawings.

Adjustably disposed in the tubular extension 10 is a tubular and longitudinally slotted needle-member, as 22, provided at or 45 near its pointed piercing end 23 with a thread-receiving eye 24, and the shank-portion of the said needle-member being provided at its end, which is slidably disposed within said tubular extension 10, with a 50 laterally projecting member 25, said member 25 serving as a fingerpiece for moving the needle-member back and forth within said tubular extension and moving it into any one of the said short slits or open portions 55 15, so as to lock the said needle-member in the desired adjusted relation to the handle-body of the embroidery needle, as will be clearly evident. The said laterally projecting member 25, also serves as a means for 60 removing the needle-member 22 from said tubular extension 10, or for inserting the needle-member in said extension, as will be fully understood.

If desired, there is pivotally disposed with-

in the groove or channel 3 of the handle-body, by means of pintles 26 which extend into holes or perforations 27 in the marginal portions 4 and 5 of the handle-body, a thread-engaging element, as 28, formed at one end with an outwardly extending finger-piece, as 29, and at its other end with a curved portion 30, having a downwardly extending thread-engaging member or clamping jaw, as 31, as clearly shown in Figures 1, 5 and 6 of the drawings. 65 70 75

Having in the foregoing described the general construction of the embroidery needle, I will now briefly set forth the manner of inserting the embroidery silk or thread 32, and the manner of using the embroidery 80 needle in connection with embroidering upon the fabric.

In inserting the thread, the latter is placed within the longitudinally extending channel or groove 3, being retained in its operative 85 relation to the handle-body by the loop or guide 21. The thread is also passed beneath the retaining or clamping jaw 31 of the device 28, being passed into and through the tubular extension 10 and the tubular needle-member 22 from which it passes through the eye 24. The manner of using the device with the fabric for embroidering the latter will be clearly understood from an inspection 90 of Figure 1 of the drawings. To release the thread, during the downward stroke, while piercing the fabric, the operator by means of the thumb presses upon the fingerpiece 29, so as to raise the jaw 31 out of its engagement, but to prevent pulling and to hold the thread taut, during the return-stroke, 95 pressure is applied by the operator upon the part 30, whereby the jaw 31 is sufficiently pressed down upon the thread 32, so as to hold the same taut and to thereby enable 100 the operator to produce a perfect and smooth surface of the embroidery which is being produced. 105

Of course, I am fully aware that changes may be made in the general arrangements and combinations of the various devices and parts, as well as in the details of the construction of the said parts, without departing from the scope of the present invention as set forth in the foregoing specification, 110 and as defined in the clauses of the claims which are appended thereto. Hence, I do not limit my present invention to the exact arrangements and combinations of the said devices and parts as described in the said specification, nor do I confine myself to the exact details of the construction of the said parts, as illustrated in the accompanying drawings. 115 120

I claim:

1. An embroidery needle comprising a handle-body provided with a longitudinally extending thread-receiving channel, a tubu- 125

lar extension at one end of said body, said extension being longitudinally slitted and having a plurality of laterally extending short slits, a needle having a portion mov-
5 ably disposed within said extension, and a laterally extending member projecting from said needle, serving as a fingerpiece and being adapted to enter into retaining engagement with a laterally extending slit in said
10 extension.

2. An embroidery needle comprising a handle-body provided with a longitudinally extending thread-receiving channel, an outwardly and inwardly curved member ex-
15 tending from said body across the said thread-receiving channel to provide a thread-
retaining loop, a tubular extension at one end of said body, said extension being longitudinally slitted and having a plurality
20 of laterally extending short slits, a needle having a portion movably disposed within said extension, and a laterally extending member projecting from said needle, serving as a fingerpiece and being adapted to
25 enter into retaining engagement with a laterally extending slit in said extension.

3. An embroidery needle comprising a handle-body provided with a longitudinally extending thread-receiving channel, a tubu-
30 lar extension at one end of said body, a needle having a portion within said extension, and means connected with the shank of the
needle for attachment of the latter to said extension, combined with thread-engaging
35 and clamping means pivotally mounted above the thread-receiving channel of said handle-body.

4. An embroidery needle comprising a handle-body provided with a longitudinally exten-
40 ding thread-receiving channel, a tubular extension at one end of said body, a needle having a portion within said extension, and means connected with the shank of the
needle, and with said extension for adjust-
45 ably connecting the needle with said exten-
sion, combined with thread-engaging and clamping means pivotally mounted above the thread-receiving channel of said handle-
body.

5. An embroidery needle comprising a handle-body provided with a longitudinally extending thread-receiving channel, a tubu-
50 lar extension at one end of said body, said extension being longitudinally slitted and having a plurality of laterally extending short slits, a needle having a portion mov-
55 ably disposed within said extension, and a laterally extending member projecting from said needle, serving as a fingerpiece and be-
60 ing adapted to enter into retaining engagement with a laterally extending slit in said extension, combined with thread-engaging and clamping means pivotally mounted above the thread-receiving channel of said
65 handle-body.

6. An embroidery needle comprising a handle-body provided with a longitudinally extending thread-receiving channel, an outwardly and inwardly curved member ex-
70 tending from said body across the said thread-receiving channel to provide a thread-
retaining loop, and a needle connected with and extending from the end of said handle-body, combined with thread-engag-
75 ing and clamping means pivotally mounted above the thread-receiving channel of said handle-body.

7. An embroidery needle comprising a handle-body provided with a longitudinally extending thread-receiving channel, an outwardly and inwardly curved member ex-
80 tending from said body across the said thread-receiving channel to provide a thread-
retaining loop, a tubular extension at one end of said body, a needle having a portion
85 within said extension, and means connected with the shank of the needle, for attachment
of the latter to said extension, combined with thread-engaging and clamping
90 means pivotally mounted above the thread-
receiving channel of said handle-body.

8. An embroidery needle comprising a handle-body provided with a longitudinally extending thread-receiving channel, an outwardly and inwardly curved member ex-
95 tending from said body across the said thread-receiving channel to provide a thread-
retaining loop, a tubular extension at one end of said body, a needle having a portion
100 within said extension, and means connected with the shank of the needle, and with said extension for adjustably connecting the needle with said extension, combined with
thread-engaging and clamping means pivotally mounted above the thread-receiving
105 channel of said handle-body.

9. An embroidery needle comprising a handle-body provided with a longitudinally extending thread-receiving channel, an outwardly and inwardly curved member ex-
110 tending from said body across the said thread-receiving channel to provide a thread-
retaining loop, a tubular extension at one end of said body, said extension being longitudinally slitted and having a plurality
115 of laterally extending short slits, a needle having a portion movably disposed within
said extension, and a laterally extending member projecting from said needle, serv-
120 ing as a fingerpiece and being adapted to enter into retaining engagement with a laterally extending slit in said extension, combined with thread-engaging and clamping
means pivotally mounted above the thread-
receiving channel of said handle-body.

10. An embroidery-needle comprising a handle-body provided with a longitudinally extending thread-receiving channel, a needle-member extending from said handle-
body, a thread-engaging and clamping
130

means comprising a fingerpiece and a clamping jaw, and a means of pivotal connection between said thread-engaging and clamping means and said handle-body for pivotally mounting said thread-engaging and clamping means directly above the thread-receiving channel in said handle-body.

In testimony, that I claim the invention set forth above I have hereunto set my hand this 18th day of June, 1921.

SAMUEL M. RIKER.
